United States Patent Office

Des. 208,038
Patented July 4, 1967

208,038

JUG

Roy C. Josephsen, Hillsdale, Joseph R. Tino, Clifton, and Charles R. Fulcher, Bloomfield, N.J., assignors, by mesne assignments, to Allied Chemical Corporation, New York, N.Y., a corporation of New York

Filed Nov. 2, 1965, Ser. No. 87,985

Term of patent 14 years

(Cl. D58—5)

FIG. 3.

FIG. 1.

FIG. 2.

FIG. 4.

FIG. 5.

FIG. 6.

FIGURE 1 is an end view of a jug showing our new design;

FIGURE 2 is a side view thereof;

FIGURE 3 is a top plan view thereof;

FIGURE 4 is an end view opposite that shown in FIGURE 1;

FIGURE 5 is a side view opposite that shown in FIGURE 2; and

FIGURE 6 is a bottom plan view thereof.

The dominant features of our design reside in the portions shown in full lines.

We claim:

The ornamental design for a jug, as shown and described.
